UNITED STATES PATENT OFFICE.

PHILIP K. DEVERS, OF LYNN, MASSACHUSETTS, ASSIGNOR TO GENERAL ELECTRIC COMPANY, A CORPORATION OF NEW YORK.

VAPOR ELECTRIC DEVICE.

1,176,661.

Specification of Letters Patent. Patented Mar. 21, 1916.

Application filed March 27, 1914. Serial No. 827,579.

To all whom it may concern:

Be it known that I, PHILIP K. DEVERS, a citizen of the United States, residing at Lynn, county of Essex, State of Massachusetts, have invented certain new and useful 5 Improvements in Vapor Electric Devices, of which the following is a specification.

The present invention constitutes an improvement in electric lighting and its object 10 is to produce light of desired color by means of an electrical discharge through conducting vapors such as an arc.

It is well known that an electrical discharge through the vapor of many substances produces light deficient in certain colors. Thus the mercury arc is notably lacking in red and to some extent in blue rays so as to have a characteristic yellowish-green color.

It has been proposed to add halogen compounds of the alkali metals to a mercury vapor lamp to give it a desired color. These alkali compounds have so low a vapor pressure that at the temperatures attainable in 25 a mercury lamp, particularly the low pressure, low temperature lamp in which they were used, they get into the arc only in an irregular and imperfect manner when vaporized by the cathode spot. The red rays 30 added thereby in the first place are not so blended with the mercury spectrum as to produce uniform light and in the second place the difficultly vaporizable compounds tend to escape from the arc to cooler parts 35 of the tube.

In accordance with my invention light of desired color is produced by associating with the mercury, or like substance whose spectrum is deficient in certain colors, a 40 compound, preferably a halogen compound, having the desired spectrum and having a vapor pressure of such magnitude that at the operating temperature of the device there will always be present in the arc path 45 a supply of the added vapor. For example, by placing in the envelop of a mercury vapor lamp of the high pressure type a quantity of a halid of tantalum, an arc of uniform color may be produced in which the 50 deficiency of the mercury arc of red and blue rays is supplied by the luminescent tantalum halid vapor which is rich in the red and blue rays.

In the accompanying drawing, Figures 1 55 and 2 are sectional views illustrating two

forms of vapor lamps of the high pressure type suitable for carrying out my invention.

In each of these forms the cathode consists of a body of easily vaporizable metal 1, such, for example, as mercury or an amalgam and an anode 2, the exposed surface of which preferably consists of platinum. A vapor device containing a halid vapor and having a platinum anode is described and claimed in a copending application, Serial 60 No. 827,621, filed by Ezechiel Weintraub. Platinum although it forms halogen compounds is not attached by the heated halogen compound in the device. Whereas other conductive materials, for example, 65 carbon may be used in the lamp, they are not as satisfactory as platinum. The tube walls are blackened after a relatively short time when using carbon as anode material. The inclosing envelop 3 consists of fused 70 quartz into which leading-in conductors 4, 5 are sealed by surrounding them with a glass having substantially the same coefficient of expansion and joining these glasses to the fused quartz by a series of intermediate zones of glass having successively 75 higher percentages of silica as the pure quartz is approached. Preferably the conductors 4, 5 consist of tungsten and are surrounded by a sodium-magnesium boro-silicate glass. They may be joined to the 80 platinum anode either by a fused joint or mechanically. Of course, the leading-in wires may also consist of platinum if so desired. In this case the graded seal must be 85 stepped up to a glass having the same coefficient of expansion as platinum, for example lead glass.

As shown in Figs. 1 and 2 the cathode chamber 6 is flattened and is nearly filled so 90 as to leave only a contracted space between the upper surface of the cathode and the roof of the cathode chamber. In Fig. 1 the cathode chamber 6 is connected with the main arc chamber 7 by means of a narrow 95 throat 8, the walls 9 of which are thickened as indicated so as to withstand the heating action of the arc. This narrow throat serves 100 to steady the arc. Into contact with the mercury body constituting the cathode is 105 placed a small quantity of the substance or substances to be used for contributing the desired rays to the arc. This material is not shown in the drawing as it is not discernible in masses. When light of a white 110

color is desired I preferably use a tantalum halid, for example, the chlorid of tantalum. This compound has a vapor pressure at the operating temperature of the device of about 5 the same order of magnitude as mercury. Although the amount of material introduced may be varied considerably, I may say for the purpose of illustration that about .007 to .1 gram of the halid will give good results. 10 The cathode chamber, which is the coolest part of the envelop, is so proportioned that no part of it will be at a temperature low enough to permit the tantalum chlorid or other halogen compound to entirely condense 15 and thus escape from the arc. In general the device should not contain zones or spots which will remain at a temperature low enough to condense the material used to modify the color of the light to such an extent as to remove it from the arc. Other halogen compounds may be used similarly, for example, compounds of niobium, bismuth, antimony, arsenic and aluminum or mixtures of these compounds. In general I 20 prefer to use a halid which either forms no sub-halid, that is, a sub-chlorid, sub-bromid or the like, or which forms a sub-halid which is also volatile to such degree that a supply of its vapor is present in the arc 25 space at the normal operating temperature of the device. The halids of niobium, bismuth and antimony contribute light having a spectrum particularly rich in blue rays. I find that it is most advantageous to use 30 compounds of the tantalum group. As a general rule materials should be used which are solid or liquid at room temperature and which therefore permit starting of the device without complicating the electrical 35 characteristics of the device.

The lamp described may be started in the usual manner by tilting so as to bring the mercury constituting the cathode in contact with the anode and then returning the envelop to the horizontal position thereby drawing an arc. The arc very soon vaporizes the halogen compound which takes part in carrying the current, the arc then emitting light having a spectrum of both the 45 mercury, or other vaporizable metal constituting the cathode, and the halogen compound.

In my opinion the halogen compound and the mercury may in some cases, as for instance with tantalum chlorid and mercury, reversibly react with each other so that at the normal operating temperature of the device there is present at the same time with the halogen compound added a quantity of 55 mercury halogen compound, for example,

mercurous chlorid and also some free chlorine and some uncombined tantalum or other metal whose halogen compound is added.

What I claim as new and desire to secure by Letters Patent of the United States, is,— 65

1. A vapor electric device comprising an envelop, means for producing an electrical discharge in said envelop, and a vaporizable halogen compound contributing light to said discharge, said envelop being proportioned 70 to operate with the coolest region at a temperature above the condensing temperature of said compound.

2. A vapor electric device comprising an envelop, a mercury cathode, an anode, a 75 halogen compound assuming a condensed state at room temperature and furnishing a light-contributing conductive vapor at the operating temperature of the device, said envelop being proportioned to assume throughout 80 during operation a temperature above the condensing temperature of said compound.

3. A vapor electric lamp comprising a mercury cathode, an anode, a quantity of 85 tantalum halid and an inclosing refractory envelop proportioned to operate throughout at a temperature at which the tantalum halid has a vapor pressure of the same order 90 of magnitude as the mercury in said envelop.

4. A vapor electric lamp comprising a mercury cathode, an anode, a halogen compound having a spectrum rich in red and blue rays, said compound being condensed 95 at room temperature and having at the operating temperature of said device a vapor pressure of the same order of magnitude as the mercury, and an inclosing envelop proportioned to assume in the coolest portion 100 a temperature sufficiently high to maintain said compound in a vaporized state in an arc between said electrodes.

5. A vapor electric lamp comprising the combination of an envelop consisting of material more refractory than glass, means for operating an arc within said envelop and a supply of a halid of tantalum, or its described equivalent, within said envelop, the envelop being proportioned to assume during the operation of the device a temperature 105 in its coolest part approximating the boiling point of said vaporizable material. 110

In witness whereof, I have hereunto set my hand this twenty-fourth day of March, 115 1914.

PHILIP K. DEVERS.
